UNITED STATES PATENT OFFICE.

ARISTIDE HARRY DES PAROIS, OF MONTREAL, QUEBEC, CANADA.

HEATING APPARATUS.

1,422,087.

Specification of Letters Patent. Patented July 11, 1922.

Application filed April 1, 1921. Serial No. 457,622.

To all whom it may concern:

Be it known that I, ARISTIDE HARRY DES PAROIS, a British subject, residing at No. 217 Boyer Street, in the city of Montreal, in the 5 Province of Quebec, in the Dominion of Canada, have invented certain new and useful Improvements in Heating Apparatus; and I do hereby declare that the following is a full, clear, and exact description of the 10 same.

The present invention relates to improvements in heating apparatus, and its main object is to provide an external casing of any suitable material, around a furnace for 15 instance, which will increase its heating properties considerably.

A further object is to provide means for supporting the baffle plates in said casing and for securing together the sides of said 20 casing.

Another object is to provide in said casing suitable doors adapted to enhance the general appearance of the device.

The invention will be understood with the 25 aid of the following description and accompanying drawing, in which:—

Figure 1 is a front elevation of the device.

Figure 2 is a vertical sectional side view.

Figure 3 is an enlarged perspective view 30 of a portion of the walls of the casing illustrating the means for securing the sides together.

Figure 4 is a perspective view of the securing device.

35 Like numerals of reference indicate corresponding parts in each figure.

Referring to the drawing, 1 are the vertical walls of the casing adapted to enclose the furnace 2. These walls preferably project from the floor 3 above the furnace, and 40 4 is a cover.

45 In the front of said casing is an open space or vertical chamber 5, which permits reaching the ash, fire box and section doors 6, 7 and 8 respectively, and which is preferably closed at its sides and back by the vertical partitions 9 and 10.

The space 5 is preferably closed in front by the sliding doors 11 and 12 which operate in the guideways 13, and on which are mounted the weights 14.

Within said casing, at suitable intervals are disposed horizontal partitions or baffle plates 15, which completely fill the space 55 provided between the walls of the casing

and furnace. Each of said partitions is preferably provided with an opening 16. The openings 16 are in zig-zag arrangement in relation to each other, in order that the gases and fumes escaping from the smoke 60 outlet of the furnace will be forced to travel around the furnace walls. A pipe 17 leading to the chimney is connected to the lower section at the bottom of said casing.

The partitions 15 are held horizontally on 65 the inner walls 1 of the casing by means of the angle bars 18 which are suitably secured thereto. The meeting ends of said angle bars 18 are adapted to overlap at the corners of the casing and are provided with registering holes 19 through which projects a clamp 20.

The clamp 20 consists of a wedge shaped member 21 having a horizontal portion 22 which projects through the opening at the 75 corner of the casing, the wedge engaging the holes 19. Vertically in relation to the horizontal portion 22 is secured a tubular member 23 which rests against the edges of the side walls of said casing and securely 80 locks said walls together. A similar clamp is secured at each corner of the casing in each row of angle bars 18, and 24 is a rod which projects through the tubular members 23 to secure together the clamps at each corner of the casing.

It will be seen that the casing is readily collapsible by removing the rods 24 and knocking out of the holes 19 the clamps 20, should it be necessary to repair or clean the 90 furnace.

The fumes escaping from the smoke outlet of the furnace enter the upper section, passing through the openings 16 in the partitions and so on, until they reach the lower 95 section at the base of the furnace when they pass through the pipe 17 into the chimney. Thus the hot fumes will form a heating jacket around the furnace walls, slowly circulating through the different sections, with 100 the result that when the fumes reach the pipe 17 they are practically cold. The zig-zag circulation causes the fumes to remain around the furnace walls, with the result that the efficiency of the furnace is greatly 105 increased. The collapsible casing is also an important feature, as it can be rapidly set up by unskilled hands.

What I claim as my invention is:—

1. The combination with a heating fur- 110

nace having a smoke outlet at its upper end, of an exterior casing enclosing said furnace and suitably spaced from the walls thereof; vertical partitions within the casing defining 5 a space or chamber in front of the doors of the furnace to provide access to said doors; a plurality of spaced, horizontal partitions secured in said casing in the space between the walls thereof and the furnace, and dividing 10 said space into a series of superposed sections, each section having a hole in zig-zag relation to the hole in the adjacent partition; and a pipe leading to the chimney communicating with the bottom section, substantially as described.

2. The combination with a heating furnace having a smoke outlet at its upper end, of an exterior collapsible casing enclosing said furnace and suitably spaced from the 20 walls thereof; a plurality of horizontal partitions forming a series of superposed sections within said casing, said partitions having holes to provide communication between

such sections and a pipe leading to the chimney communicating with one of said sections, substantially as described.

3. The combination with a heating furnace having a smoke outlet at its upper end, of an exterior casing enclosing said furnace and suitably spaced from the walls thereof; 30 vertical partitions in said casing defining a space or chamber in front of the doors of the furnace to provide access to said doors; a plurality of partitions within said casing forming a plurality of sections, said partitions having holes to provide communication between such sections; a pipe leading to the chimney communicating with one of said sections; and doors closing the said space or chamber, substantially as described. 35

Signed at Montreal, Quebec, Canada, this 26th day of January, 1921.

ARISTIDE HARRY DES PAROIS.
